UNITED STATES PATENT OFFICE.

FRANK SHAW, OF NEW YORK, N. Y., AND WILLIAM A. CHILDS, OF ENGLEWOOD, NEW JERSEY.

TELEPHONE-EXCHANGE SYSTEM AND APPARATUS.

SPECIFICATION forming part of Letters Patent No. 278,613, dated May 29, 1883.

Application filed January 19, 1883. (No model.)

To all whom it may concern:

Be it known that we, FRANK SHAW, of New York city, and WILLIAM A. CHILDS, of Englewood, New Jersey, have invented new and useful Improvements in Telephone-Exchange Apparatus and Systems, of which the following is a specification.

Our invention relates to improvements in telephone switch boards or tables and other necessary apparatus for receiving orders for connections and disconnections from subscribers, and for giving and receiving orders for trunk-line connections and disconnections, and also for making such connections and disconnections, the former being made between subscribers' wires of one group or central office and the latter between the subscribers' wires of any two groups or central offices through trunk-lines for subscribers' use between such central offices.

The objects of our invention are to save space and expense by reducing the size of the switch-board; to save in the number and expense of operators; to save confusion, delay, repetition, and errors, and secure quiet, promptness, and accuracy, and at the same time to put the whole switch-board under the control of such operators—one or more. We attain these objects by the mechanism illustrated in the accompanying four sheets of drawings, in which similar letters refer to similar parts throughout the several views.

Figure 1 is a perspective view of the switch-board top and apparatus; Fig. 2, a cross-sectional view of a part of the switch-table top, showing three tubes, T, in perspective and one in vertical section, with part of the bottom B', rod R, and cord D, in section, with four plugs, G, in perspective; Fig. 3, a rod, cord, spring, and plug in perspective; Fig. 4, a switch in front view; Fig. 5, a plan of two groups of central offices connected together; and Fig. 6, the same, with the addition of the apparatus and lines of two subscribers' stations connected with central office No. 1 and two more connected with central office No. 2.

In each of the groups Nos. 1 and 2, Fig. 5, the outfit of three subscribers' operators O and the outfit of one trunk-operator O' are shown. In Fig. 6 only one of the outfits of operators

O is shown in each central office, for convenience merely. Each subscriber has two wires—a call and private wire—connecting him with his central office, and between the central offices extends a calling (one) wire from each office to the other, also two trunk-wires.

The same apparatus is intended to be used whether the two switch-tables are in separate offices or separated in the same office, as for use in large exchanges. In one system now in use a long and high continuous switch-board is employed—say sixty (60) feet long and six (6) feet high—for less than one thousand wires and subscribers, before which the operators rush back and forth in more or less confusion to perform their duties. In another system desks having about fifty (50) wires and apparatus for connection are provided for each operator, and increased as the subscribers increase. In still another system duplicate switch-boards are provided for each additional switch-operator connected with extension lines in order to keep these operators separate, prevent confusion, and enable operators in charge of any particular section of a switch-board to make connections with subscribers' lines, belonging normally to other sections. In each of these systems, and in all others so far as we know, the operators, whether the board be entirely upright or placed upon a desk and in part upright, are placed upon one side only of the switch-board, the board being arranged, disposed, and adapted for this purpose; and where more than one operator operates either of these boards he or they must do so from a position beside the first operator, the result of which is inevitable interference of each operator with every other in the necessary manipulations.

In our invention the apparatus is arranged in the form of a table, around which the operators may sit, having the whole top of the table within the reach of each operator, one or more. Fig. 1 shows the top part of such a table. C in Fig. 1 is a case containing, say, four hundred small metallic tubes, standing closely together, like so many candle-molds in a frame. This case is made as follows: At top and bottom it has a board or plank—say thirty-two (32) inches long, eight (8) inches

wide, and two inches thick—perforated with four hundred (400) holes—say of seven-sixteenths ($\frac{7}{16}$) inch diameter. These holes are disposed in four sections, each having ten (10) holes on a side, making one hundred (100) holes in a section, four hundred (400) in all, and three-quarters of an inch from center to center. These holes receive tubes T, which are twenty-six inches long and extend between the two planks B B', and, say, half-way through the same, at the ends. Each hole in the bottom plank, B', has the end of a subscriber's wire inserted therein, as shown at W, Fig. 2. This wire is secured by simply driving the lower end of the tube into the hole, the result of which is that each tube becomes practically an extension of the particular subscriber's wire inserted in that particular hole. The bottom holes are made preferably of the same size as the bottom ends of the tubes T, so as to drive solidly and hold the wire W firmly, and at the same time make and maintain electrical contact. The top holes are made of such size as to allow the tubes to pass easily from above and through them into the lower holes. The boards B and B' may be made from two or more layers or pieces of wood secured together in any usual way.

P P P P are plates of metal provided with holes made continuous with those in B. These plates are ground-plates, having each a ground-connection, and they may be made in sub-sections, if convenience requires. These plates P rest upon the top of the board B with sufficient space between their under sides and the upper ends of the tubes T to insure insulation therefrom.

Figs. 2 and 3 show a rod, R, and flexible conducting-cord D, with plug G, terminating the same. The rod R is cut away at top O², to receive a flexible flat spring, S, preferably made of German silver. The rod R, being dropped into a tube, T, from above, will fall by its own weight within the tube T, drawing the cord D after it until the broad part of the plug G rests upon the plate P, to which the tube T belongs. The spring S is so attached to the rod R as to project beyond its surface and press with sufficient force against the inside of the tube T to effect electrical contact. Consequently when a plug G rests upon a plate P a ground-connection is established from the subscribers' wires. Each one of the four hundred tubes T has its rod R, cord D, and plug G, and every one of the four hundred wires being so connected, atmospheric electricity will be conducted to the ground safely, and all the other advantages incident to a normal ground-connection will be secured.

Among these advantages are the escape of induced currents of a battery-current from a cross or accident, thereby preventing the ringing of the bell in subscriber's office, and also other advantages arising from having the subscribers' private lines electrically directly connected with a common plate or conductor in the central office. Between these plates and

the subscribers' offices there are, upon the private lines, no lightning-arresters and no annunciators, telephones, or other instruments or coils causing resistance, and no resistance except such as is offered by the lines themselves.

Plates P' P', placed on each side of the ground-plates P, are battery-plates. P² P² are also battery-plates, having circuit-breakers or pole-changers in their circuits. The first, P' P', bear numbers 0, 1, 2, 3, &c., which are used to number each row of holes in the plates P, for the guidance of the operators.

P³ P³ P³ are simply connecting-bars, and are provided with holes to receive the plug G for the purpose of connecting any two wires. Most of these last are used to connect subscribers' wires of the same group or table; but when there are two or more groups or tables in the same or different offices connected by trunk-lines, as shown in Figs. 5 and 6, we reserve a sufficient number of these bars—say Nos. 1, 2, and 3—and connect them with corresponding bars on other tables by trunk-lines U U' U², &c., in a manner and for purposes to be described hereinafter; or, if preferred, the trunk-lines U, U', and U² can be connected with the tubes T in the same manner as subscribers' wires, when connections can be made as desired, in the regular way, through plates P³. Each of the bars or plates P³ is provided with a key, K, which, on being depressed, makes contact with the battery strip or plate P⁴, for the purpose of ringing the bell of a subscriber in case he does not answer promptly after he has been connected, and without disconnecting for that purpose.

A A are transmitters located conveniently at each corner of the table—one for each operator, say. The receivers are shown in Fig. 5. We have shown a table suitable for four operators, located one on each side of the table. Each one of these operators can reach and make any connections upon the whole table. The number of plates P³ used by us is thirty-five on each side for the connections of four hundred subscribers. This number may be increased, as required by increased calls for connections, by making them narrower, placing them nearer together, or cutting them up into sections. Each operator is supposed to have, for convenience, a receiving-instrument secured to the head and ear, so as to leave both hands free to manipulate the apparatus. This switch-table may be operated upon several systems. We prefer to employ the system known as the "Law system," and shown in the Letters Patent granted to Frank Shaw, October 21, 1879, No. 220,874, of which the system herein shown is in some respects an improvement.

We do not limit ourselves to the numbers (four hundred) of wires terminating in each table, and of sections, (four,) nor to the exact dimensions given, as these may all be varied somewhat without avoiding our invention.

The terminals and connecting-bars are ar-

ranged in a horizontal plane on the top of a table adapted to the convenient approach of the operators from all sides, and we consider this the best arrangement; but we are aware that slight changes may be made in the relations of the bars to the top of the table by a variation from the horizontal to a considerable extent, but not without detriment to the convenience of manipulation. We are by this means able to place the operators on different sides of the board, more or less facing each other, and consequently in positions to avoid mutual interference during manipulation. It is evident that two operators may be placed opposite each other at such a board or table, and also that the table may even be made more than four-sided and adapted to more than four operators, if desired, without going beyond the scope of our invention. So, also, as to the location of the terminals in the center of the board. We are aware that the relative positions of the bars and terminals may be exchanged, the bars being located in the center of the table and the terminals upon each side of them. The terminals might also be arranged in a circle around bars in the center, so as to be accessible to more than two or four operators; but for exchanges of the sizes now required we prefer the arrangement as shown.

In Fig. 6 two central offices, groups or tables, instruments and apparatus, and also the instruments and apparatus of two subscribers of each central office, are shown. The four subscribers' instruments and apparatus are shown in what may be called the "normal state," with the receiver on the hook and the switches under the control of their several springs. In this condition the circuit of the subscribers' signal or calling wire, which has the instruments of the subscribers' listening-operators O in circuit at the central office, passes through each one of the subscribers' switches by way of the upper bar, which is continuous across the switch, and therefore this circuit is without resistance, normally, outside of the central office, except such as is offered by the line itself. In the same condition the circuit of the subscriber's or private wire, each one, starting from the tube T of the table at the central office, passes to that bar of the switch on the side approached which lies longitudinally, and thence by way of the line D' , the receiver-hook lever, the line E , the opposite longitudinal bar, (the two being separated or insulated from each other,) by way of the bell-helix, to the ground. In this condition of the parts the telephone-instruments and battery are cut out of the private-wire circuit; but when the receiver is lifted from its hook the contact of the hook-lever with the contact-point of the line I brings them into the private or subscriber's wire, and in this condition of lines, apparatus, and circuits the conversation between subscribers can be conducted. When, however, the push-

button is pushed in and the switch-spring thus overcome, the private-wire contact rests upon the lower bar, which is continuous across the switch, and the circuit goes direct to the bell and ground, thus still providing for calling the subscriber from the central office by ringing his bell. At the same time the telephone-instruments and battery are thrown or switched into the signal or call-line circuit, which then passes by way of one of the upper springs, the longitudinal bar of the switch on one side the wires D' , F , L , and H taking in the secondary coil of the transmitter and the telephone-instruments, and passing out at the other upper contact-spring to the calling or subscriber's wire beyond, and the local-battery circuit being closed through the primary coil of the transmitter by way of the wires I , F , and J .

The method of operation will then be as follows: The operator, receiving the order, say, to connect 121 with 221 by the signal-wire and receiving-instrument A' in its circuit, will take the plug G 121 in one hand and the plug G 221 in the other hand and ring the bell of each by touching the plugs to the nearest plate P^2 . He will then connect those subscribers' lines (121, 221) by inserting both plugs into any one of the plates P^3 reserved for local connections and not in use. When the order to disconnect is received from either 121 or 221, the operator removes the plugs from the plate P^3 , and, giving each a touch to one of the battery-plates P' , sends signals—one to each party—over their private wires, that their lines are disconnected. Each receiving-instrument having a different set of subscribers' offices on the signal-wire with which it is connected, it may be that the order to disconnect may not come to the operator who made the connection, since the party first called for, and not the calling party, may give the disconnect order, but may come to either of the other operators sitting around the table, or rather will come to the operator on whose signal-wire the subscriber giving the order is located. On receiving this order, being able to reach the entire table, either of the operators can readily execute the order. Both the connections and the disconnections are made in silence, and in obedience to orders received at the ear of the one operator and without the knowledge of the others. By bringing the private wires to ground-plates or conductors directly, without any resistance or instruments causing resistance in the same, many advantages are obtained. Its functions are to carry off atmospheric electricity, to permit the escape of induced currents, to take a battery-circuit from a cross or accident and prevent the ringing of the subscribers' bells, and to accomplish other manifest advantages. Formerly the practice was to repeat the disconnect order over the signal-wire from the central office to the subscriber, thereby giving the subscriber notice of disconnection as well as the switch-board-operator who disconnects. The tend-

ency of this practice in large exchanges may be to overload the signal-wire with work, while the private wire is idle; but by tapping the plug upon the battery-plate, as above mentioned, a bell is rung in the subscriber's office through the private wire, thus relieving the signal-wire of a part of its work, and saving all talking back of the listening-operator, who is consequently also relieved of a part of his former labor, and materially increasing the amount of work that can be done by the apparatus and a given number of operators.

S' S' are switches substantially like those shown in the Letters Patent of Frank Shaw, previously referred to. Three of the switches S' keep the several receiving-instruments in circuit with the subscribers' signal-wires; but in case an order comes for connection with a subscriber's wire of another group or office, provision having been made therefor, as shown in Figs. 5 and 6, the procedure is as follows: Inserting the plug G—say No. 2—after the signal, as described, into one of the connection bars or plates P³, reserved for trunk-line connections—say No. 1, 2, or 3—the operator puts his finger on the button of his switch S', and, pressing the same, thereby switches his instruments into the circuit X X, (or X' X'), which connects with the group to which the desired number belongs, and requests the operator there, O', to connect, say, No. 3 with No. 1, by saying: "Connect 3 with 1," or "Three one," which being done, after the usual signal to No. 3, the two subscribers will be found in connection through line U, which connects the two trunk-line bars No. 1 for conversation. The order to disconnect may be sent in the usual manner through the operator first called by No. 2, and through him to the operator O', who received the order to connect No. 3 with No. 1; or, if this order comes from No. 3 to any operator at the group or table to which No. 3 belongs, the status is evident at a glance, and the order is sent to the group or table to which No. 2 belongs through the operator O' on the trunk-signal wire X', and executed in the usual way, (X or X', according to the group from which the order emanates.) The line X X, which, beginning at the ground G' at the left, passes into the switch S' near the operator O of the upper side of the group No. 1, or table, Fig. 5, also passes into the switches S' near the other two operators O, and also into the switch near the operator O' of the same group, though this is not essential, as will appear further on. It will be observed that it enters and passes out at the bottom part of each one of these switches, but on reaching the switch S' of the group No. 2, near the operator O' of that group, enters that switch and emerges to ground at its top. This arrangement enables any one of the three operators O of group No. 1 to signal and communicate with the operator O' of group No. 2 by simply depressing his switch-button and throwing his instrument into the circuit X X, and

thus without disturbing either the two other operators O or the operator O' of group No. 1. The line X' X' of group No. 2 connects the switches and operators O of that group with the operator O' of group No. 1 in a similar manner. The operators O' of both groups receive and execute the trunk-line connection and disconnection orders of the other group.

It will be seen that each trunk-line operator O' has for his duty only to receive orders for trunk-line connections from other central offices or other tables similarly connected. These trunk-signal lines will each pass from the outfit instruments of the operator O' of each office or table into the other offices or to other tables, and in such connection with the switches of each additional table that any one of the subscribers' operators of any table may switch into any one of such trunk-signal lines and give orders for trunk-line connections. The object of this arrangement is to direct only such orders as are to be filled by him to each trunk-line operator O', and thereby relieve him from any necessity of listening to or hearing orders for other operators and selecting those intended for himself. By this means evidently the operator O' can receive orders for and make a much larger number of connections than he otherwise could, which has thus become his sole function; and one operator receives the orders for trunk-line connections from all the other offices or tables, thereby keeping down the number of such operators, reducing expense, and promoting accuracy and dispatch of business. In case any operator O', on receiving an order for a connection, finds that it cannot be executed for any reason, he can notify the office or table from which the order emanates of the fact, even after the operator giving the order has switched his instruments out of the line, by switching his outfit out of the line (X X or X', as the case may be) over which the order came and into the line through which the subscribers' operators O of his table transmit their trunk-line orders, such line being taken through the switch of the operator O' for that purpose; and the notice is received by the trunk-line operator on that line, who can either tell his associate subscribers' operators, *viva voce*, the fact, leaving it to the proper one to notify the subscriber calling for connection, or the trunk-line operator, glancing at the trunk-line bar engaged in his table for that connection, can himself signal directly to the calling subscriber by any specific number of taps on his bell, or in any ordinary manner; but this last-mentioned arrangement may be omitted.

The table-top is about thirty-two (32) inches square, and can be reached at all points by any one of four operators sitting around it. We have been able to place and operate four hundred (400) lines and circuits in one table. When the number of wires centering in one group is too large for one table, we provide another table of a similar construction, connected by

trunk lines, as shown in Figs. 5 and 6, and whether these additional groups or tables are in the same room or office or located at a distance, the connecting apparatus between them 5 is the same, and so likewise is the method of operation.

As shown, the rods R R are solid, and operate by their weight, so as to drop within the tubes automatically when the plugs G G are 10 withdrawn from the plates P³ and released, the broad part of the plugs G being drawn down thereby onto the ground-plates P, thus maintaining a normal ground-connection when the several lines are not in use for conversation 15 between subscribers; but in whatever position the rod may be, the electrical circuit connecting with the tube and its line is always complete through the German-silver spring S.

We are aware that a continuous contact may 20 be effected by any other usual means for securing proper rubbing pressure between the rod and the tube, but have found the light spring shown most satisfactory. We contemplate the use of a rubber strip or a spiral or 25 other spring, instead of the weighted rods R, to draw the contact-springs and the flexible cords automatically into the tubes T, with the plug G bearing upon the ground-plate P, as described; and we do not desire to limit our 30 selves to the use of the tubes T and rods R standing upright, since it is evident that they may be placed horizontally and still be made to operate and effect very great economy of space, especially where the number of connections may not be so great as to require more 35 than one operator.

It is evident that the relations between the tube T and the rod R may be reversed. The rods will then be stationary and in contact 40 with the subscribers' wires in the plank B, and the tubes will be movable, attached to the flexible cords, and capable of performing the functions of the rods in a similar manner; or one or more rings may be substituted for the 45 tube, moving up and down on the rod under the control of a weight or of a spring; or any other usual form of guide may be substituted to control the movement of the circuit-maintaining spring or other device. We also contemplate the substitution of a permanent connection between each subscriber's wire in the 50 plank B and the flexible cord D by means of a spiral spring attached in any usual manner to each. The spiral spring would then act both 55 as a spring to automatically withdraw the cord and plug and also as part of the circuit. These springs may be made movable in tubes made of wood or other suitable material, or held and kept separate from the adjoining 60 springs by any usual kind of guides.

Our system of numbering the subscribers' wires and plugs is as follows: Each one of the four plates P contains one hundred plugs. That to the left contains the one hundreds, 65 the next to the right the two hundreds, the next the three hundreds, and the next the four

hundreds. Each hundred being thus grouped, any number can be found instantly. Each one of these sub-groups or sections has on each of their four sides numbers, as shown, from 0 to 9, 70 opposite each row of ten holes. Consequently the eye and hand of the operator instantly recognize the location of the plug of any subscriber and subscriber's wire, and he may therefore make the connections and disconnections instantly, since the operators sitting upon either side of the table can easily follow the decimal arrangement of the plugs between 1 and 100 in each section.

G' is the ground-wire of the trunk-signal 80 line near the telephones of the subscriber's operator's outfit.

G² is the ground-wire of the subscriber's call-line near the same.

G³ is the ground-wire of the trunk-signal 85 line near the outfit of the trunk-signal operator.

G⁴ is the ground of the plate P.

G⁵ is a ground for the battery-plates P P.

G⁶ is the ground of the subscriber's ends of 90 the subscriber's calling-wire.

The several switches shown in the drawings are in themselves substantially alike, although they appear in two forms. In every instance the telephones and battery-cell are connected to the two center contacts. In the switch having one coiled spring these contacts are the two center flat springs, and are constantly in contact with the two insulated longitudinal bars of the switch. In the switch provided with two coiled springs these latter are used 100 as parts of the lines on each side of the outfit, and connect with the two longitudinal insulated bars, which are themselves movable in this instance by means of arms extending therefrom, to which the coiled springs are attached. We 105 show in the drawings three distinct and separate combinations of lines with this switch. Generically the combinations are the same in the three; specifically they are different. The first of these is like that found in the Shaw 110 patent, and is shown in Fig. 6—subscribers' outfits Nos. 1, 2, 3, and 4. The second is shown in Figs. 1, 5, and 6—subscribers' operators' 115 outfits; and the third is shown in Figs. 5 and 6—trunk-signal-operators' outfits. In all the outfit is connected by the two center contacts with two insulated bars, and they are always 120 in contact therewith, and two circuit-wires are brought to the two contacts at the two ends, one circuit to each, into one of which circuits the outfit is normally held by the coiled spring or springs, and into the other of which circuits the outfit may be thrown by simply pushing in the button. In the first of these 125 three cases the outfit is normally looped into the private wire, and may be thrown, by moving the push-button, into the subscriber's calling-wire; in the second the outfit is normally looped into the subscriber's calling-wire, and may be thrown into the trunk-signal wire; in 130 the third the outfit is normally looped into one of the trunk-signal wires leading from another

office or offices, table or tables, of the system to that one at which the trunk-signal outfit is placed to receive trunk-signals, and may be thrown, by moving the push-button, into the 5 trunk-signal wire going from the office or table at which the outfit is located to another office or table.

It is of course understood that in mentioning the battery-plates and battery for signaling we include all equivalent signaling apparatus. The current may be derived from a magneto-generator connected with the same plates, in place of a battery and circuit-breaker, as shown. We understand that such an 15 arrangement would be equivalent to that shown in the drawings.

We hereby disclaim, as far as this specification and these Letters Patent are concerned, all the inventions shown, described, and 20 claimed or to be claimed in our original application No. 40,442, filed August 22, 1881, and not claimed herein, and this disclaimer is in favor of our said original application only. This disclaimer is intended to cover, and does 25 cover, every invention not specifically claimed in the several claims of this specification, and all inventions shown, described, or otherwise found herein and also found in the said original application, but not so claimed herein, are 30 left in the said original application No. 40,442.

We claim as our invention—

1. In a telephone-exchange system, a switching apparatus provided with the following elements in combination: first, a tube, T, or 35 its equivalent, arranged to permit or facilitate a sliding electrical contact therewith; second, a conducting connection-cord, D, or its equivalent, arranged and provided at one end with devices to effect continuous sliding electrical 40 contact with a tube, T, or its equivalent, and at the other end with a plug and connection devices, substantially as shown and described.

2. In a telephone-exchange system, a switching apparatus provided with the following elements in combination: a stationary tube, T, or 45 its equivalent, forming the terminal of a subscriber's line, a weighted sliding rod, R, and spring S, arranged to make and maintain automatically continuous sliding electrical contact between the tube and rod, and flexible 50 connections and switch-board plate, or their equivalents, substantially as shown and described.

3. In combination, the subscriber's terminal, consisting of the tube T, the weighted 55 sliding rod R, in frictional contact with the tube and a flexible connection, the ground-plate P, and the signal-plate P', as shown and described.

60 4. In combination, the subscriber's terminal, consisting of the tube T, the weighted sliding rod R, in frictional contact with the tube, and the ground-plate P.

65 5. In a switching apparatus for a telephone-exchange, subscribers' terminals consisting of tubes T T, weighted sliding rods R R, in fric-

tional contact with the tubes, and flexible connections, in combination with one or more connection-plates, P³.

6. In a switching apparatus for a telephone-exchange, subscribers' terminals consisting of tubes T T, weighted sliding rods R R, in frictional contact with the tubes, and flexible connections, in combination with one or more connection-plates, P³, placed horizontally at right 70 angles to the tubes.

7. A switching apparatus in a telephone-exchange, provided with subscribers' terminals consisting of tubes T T, weighted sliding rods R R, in frictional contact with the tubes, and 80 flexible connections, one or more ground-plates, P, one or more signaling-plates, P', one or more battery-plates, P² P², and one or more connection-plates, P³.

8. In a telephone-exchange, a switch-table 85 with four sides, having its subscribers' terminals located or massed in or adjoining the center of the table, and its series of connecting devices on each side of the same for subscribers' or trunk lines.

9. In a telephone-exchange, a switch-table 90 with four sides, having its subscribers' terminals located or massed in or adjoining the center of the table, and one or more circuit-closing devices for signaling on each side of the 95 same for signaling subscribers.

10. In a telephone-exchange, a switch-table with four sides, having its subscribers' terminals located or massed in or adjoining the center of the table, and its connection and signaling plates on each side of the same.

11. In a telephone-exchange, a four-sided switch-table having its subscribers' terminals located or massed in or adjoining the center of the table, the connection and signaling plates 105 on each side of the same for subscribers' and trunk lines, and at the corners of the table an operator's outfit, whereby the operator may receive orders for connection and disconnection and execute the same.

12. In a telephone-exchange system, a trunk-signal line consisting of a line extending between two central offices for giving and receiving signals for connections and disconnections between two central offices, a subscriber's signal-line consisting of a line extending between a subscriber's station and a central station for giving and receiving signals for connections and disconnections between subscribers, provided with a listening-operator's 110 outfit normally located in the subscriber's signal-line, and a switch combined and arranged to switch the operator's outfit at will from the subscriber's signal-line into the trunk-signal line.

13. In a telephone-exchange system, a subscriber's signal-line consisting of a line extending between a subscriber's station and a central station, for giving and receiving signals for connections and disconnections, trunk-signal lines consisting of lines extending between two central offices, one for giving and another 115

for receiving signals for connections and disconnections between two central offices, provided with a listening-operator's outfit, normally located in one trunk-signal line, and a switch combined and arranged to switch the operator's outfit at will from that trunk-signal line into another trunk-signal line.

14. The combination of the connection-plates P^3 , the battery-plate P^4 , and keys K , for the purpose of ringing the subscriber's bell after connection of two subscribers has been made, and without disconnecting the same.

15. In combination, a ground-plate, P , and an automatically-operated plug, G , brought into contact for the purpose of grounding the subscriber's wire.

16. The combination, with the base B' , having holes H therein, of the tubes T , brought into electrical contact by forcing the tubes into the hole, in which the end of the wire has been previously inserted.

17. In a telephone-exchange switch-board, the following elements in combination: first, a table with horizontal top; second, the central-office ends of subscribers' lines, entering the table from below and terminating in the table-top; third, connecting-cords for connecting any two subscribers' lines, which are automatically withdrawn below the table-top when the subscribers' lines are disconnected.

18. In a telephone-exchange switch-board and apparatus, the following elements in combination: first, a table with horizontal top; second, the central-office ends of subscribers' lines, entering the table from below and terminating in the table-top; third, automatically withdrawn connecting-cords and apparatus; and, fourth, call or signal wire and operator's outfit for re-

ceiving orders to connect and orders to disconnect, located beside and within reach of the subscribers' lines, terminals, and connecting-cords.

19. In a telephone-exchange system, a trunk-signal wire, consisting of a line extending between two or more (a series of) central offices or tables, provided with an operator's outfit, located in the trunk-signal line at one of the central offices of the series only, and provided at each of the other central offices with one or more switches, (one for each operator,) arranged to switch the outfit (one or more) of one or more subscribers' operators into the trunk-signal line, for the purpose of transmitting orders for connection and disconnection to one central office from all the others of the series.

20. In a telephone-exchange system, subscribers' wires normally grouped and brought directly to one or more common ground-plates or conductors, without the intervention of an annunciator, telephone, or other coils or devices offering resistance to the electrical current on or in the wires between the central office common ground-plate or conductor and the subscribers' offices.

21. In a telephone-exchange system provided with a call-wire and with an independent private wire, the call-wire provided with a subscriber's operator's outfit at the central office, and the private wire provided with battery-plate for signaling to the subscriber in reply to a call for connection or disconnection, as shown, or its equivalent.
